ILLUMINATED PANEL

Edwin A. Neugass, White Plains, N. Y.

Application July 3, 1951, Serial No. 235,043

12 Claims. (Cl. 40—130)

The present invention relates to improvements in panels, such as those used for mounting aircraft instruments, and is particularly directed to panels of the described character which are internally illuminated.

Internally illuminated panels have heretofore been proposed, as in U. S. Patent No. 2,518,726, issued August 15, 1950, in which a core or body of a transparent, light transmitting material or medium is laminated between sheets of translucent light colored material and layers of dark colored opaque material are formed on the surfaces of the translucent sheets, with the opaque layer facing the viewer being penetrated to expose areas of the underlying translucent sheet defining the desired characters or indicia. In such panels, the light-transmitting core or body is internally illuminated and transmits the light to its portions remote from the light source by reflection of certain of the light rays back into the body at the opposite surfaces of the latter covered by the light colored translucent layers, while certain other light rays directed at the surfaces of the core or body pass into the adjacent translucent sheets and are transmitted by the latter to the surface of the panel in the penetrated areas of the opaque outer layer, or facing, to illuminate the indicia or characters defined by the openings in the latter.

An object of the present invention is to provide translucent layers or sheets in panels of the described character which transmit the non-reflected light to the surface of the panel at the penetrated areas of the opaque outer facing or layer with as little loss as possible.

Another object is to provide an panel of the described character which is constructed so that the portions of the translucent sheets remote from the source of light transmit a greater proportion of the light rays impinging thereagainst than do the portions of such sheets closer to the source of light so that the illumination of the indicia or characters defined by openings in the opaque outer layer or facing is uniform without regard to the distances such indicia or characters are located from the source of light.

A further object is to provide a panel of the described character wherein the efficiency of the internal light transmission is improved.

Various further and more specific objects, features and advantages of the present invention will clearly appear from the detailed description given below taken in connection with the accompanying drawings which form a part of this specification and illustrate, merely by way of example, several embodiments of the invention.

The invention consists in such novel features, arrangements and combinations of parts as may be shown and described in connection with the articles herein disclosed, by way of example only, and as illustrations of preferred embodiments.

In the drawings:

Fig. 1 is a front elevational view, partly broken away and in section, of one embodiment of the present invention;

Fig. 2 is a cross-sectional view taken along the line 2—2 of Fig. 1;

Fig. 3 is a cross-sectional view similar to Fig. 2, but of a panel constructed according to another embodiment of the invention and having a light source installed therein; and

Fig. 4 is a cross-sectional view, on a greatly enlarged scale, taken along the line 4—4 of Fig. 3.

In panels of the kind shown in U. S. Patent No. 80 2,518,726, light is transmitted through the central core or

body by reflection of certain of the light rays emitted from the light source back into the core at the opposite surfaces of the latter which are covered by the translucent layers or sheets, while certain other light rays 5 passing through the core are not reflected, but instead are passed through the translucent layers to emerge from the panels at the penetrated areas of the outer opaque surfacing or layer. Whether light rays will be mostly reflected back into the interior of the panel or will 10 mostly pass into the translucent sheet for emergence at the penetrated areas of the opaque outer layer has been found to depend upon the angles at which the rays of light impinge against the surface of the translucent sheet facing the core. Thus, light rays which impinge against the inner surface of the translucent sheet at an angle from the normal greater than a critical angle are reflected back into the body or core medium, while those rays impinging at angles to the normal less than the critical angle are absorbed in the translucent sheet and transmitted by 15 the latter to the surface of the panel.

According to the present invention uniformity of the intensity of light transmitted by the translucent sheet to the front surface of the panel at the penetrated areas of the opaque facing is achieved by curving the front of 20 the panel so that the portions of the front translucent layer remote from the light source incline toward the latter to permit a greater portion of the light rays impinging against such remote portions to impinge thereagainst at angles less than the critical angle. Thus, the tendency 25 of the light rays, emitted from a source within the panel, to impinge against a flat front translucent layer at angles, relative to the normal, which increase progressively with the distance from the source is counteracted so that similar proportions of the light rays are transmitted by the 30 front translucent layer at all distances from the light source.

In Figs. 1 and 2, a laminated panel 10 is illustrated embodying this feature of the present invention. The panel 10 includes a core or body 11, which provides the 35 structural strength and is, therefore, preferably made thicker than the other laminae or layers. The core or body 11 is light-transmitting and preferably formed of a plastic material, such as, for example, one of the class of acrylic resins and their polymers and copolymers, 40 methyl methacrylate having been found most suitable, although other light transmitting materials, such as, quartz, may be employed. The core or body 11 is formed with a convex front surface 12 (Fig. 2) and is surrounded by a light colored translucent sheet or layer 45 13, of appreciable thickness, which is preferably formed of a plastic composition more fully described herein-after. The panel 10 is completed by an outer layer or facing 14 of dark colored, preferably black, material, a plastic of the class of polyvinyl or vinyl resins or materials, their polymers or copolymers being preferred.

The lamination of the core 11, sheet 13 and outer layer 14 may be performed by coating the several confronting surfaces thereof with a suitable adhesive and then pressing the sandwich together to squeeze out the 50 excess adhesive and assist in forming the bond. Another method of performing the lamination is to place the core 11 in a press with heated platens between sheets of the translucent plastic material and bond them together by means of heat and pressure. This lamination is then 55 placed in the press between layers of opaque plastic material and a new lamination made by application of heat and pressure.

After the lamination has been formed as above, a bore or opening 15 is formed therethrough to accommodate a panel light of conventional form, such as, panel lights manufactured under part #A4295, by Grimes Mfg. Co., Urbana, Ohio, and the opaque outer layer 14 is engraved away at suitable locations on the curved front of the panel, as at 16, to thereby expose the underlying portions of the translucent sheet 13 for defining the desired indicia or characters.

Referring to Fig. 2, it will be seen that light rays, such as the rays A₁ and A₂, emitted from a source A in the bore 15 impinge against the curved surface of the translucent sheet 13 facing the light transmitting core at substantial angles to such surface, by reason of the con-

vexity of the latter, so that the translucent layer is effective to transmit such rays to the front surface of the panel at the openings 16. Were the front surface of the panel flat, as in the panels previously proposed, the light ray A₂ directed toward the portion of the panel remote from the light source A would form an angle relative to the normal to the front surface exceeding the critical angle and would, therefore, be reflected back into the body 11, rather than being transmitted forwardly by the translucent layer 13. It is apparent then that the curvature given to the front face of the panel 10 according to the present invention is effective to equalize the intensity of the transillumination of the indicia or characters defined by the openings 16 without regard to the distance such openings are located from the bore 15 in which the light source is disposed.

It has further been found that the only function of the light transmitting core or body, around which the existing panels are constructed, other than the transmission of light through the interior of the panels, is to provide structural strength to the panels. It will be appreciated that certain losses are experienced in the transmission of light from the source through the light-transmitting material of the body 11 in Figs. 1 and 2, and I have found that the efficiency of the light transmission is improved from 8% to 25% by replacing the solid core or body 11 with an air space. Such a panel is provided according to the present invention, by forming the outer opaque layer or sheet as a hollow structural box having suitable openings formed at the front to define the desired indicia or characters, and supporting the translucent sheet as a coating on the internal surface thereof.

Referring to Fig. 3, a panel 17 is there illustrated and shown to include a hollow box, preferably formed of metal, and having a flat rear wall 18 and an outwardly convex front wall 19 formed with suitable indicia defining openings 20. A layer 21 of translucent, preferably plastic material, more specifically described hereinafter, is formed on the interior surfaces of the walls of the hollow box structure, and registering openings are formed in the front and back of the panel to receive a panel light 22 of the conventional kind heretofore noted. Rays of light emitted from the panel light 22 are transmitted by the air in the hollow interior of the panel 17 and impinge against the inner surface of the translucent layer 21 to be either reflected back into the air space or transmitted through the translucent layer for emergence at the openings 20 depending upon the angles at which such light rays impinge against the surface of the layer 21.

As in the first described embodiment, shown in Figs. 1 and 2, the curved front of the panel 17 tends to equalize the intensity of the light transmitted by the translucent layer at the openings 20 spaced at various distances from the light source, and in the panel 17 this equalization is further promoted by the reduction in the losses experienced during internal transmission of the light to the remote portions of the panel as effected by the substitution of air as the light transmitting medium in place of the acrylic material of the panel 10.

The translucent layers 13 and 21 of the embodiments illustrated in Figs. 1 and 2 and Fig. 3, respectively, perform several functions. Such translucent layers reflect light rays impinging thereagainst at angles greater than the critical angle back into the interior of the panels, transmit other light rays to the surface of the panel at the indicia defining openings of the outer opaque layer, and also reflect ambient light striking against the portions of their outer surfaces uncovered by the indicia defining openings so that the indicia are readily visible in daylight by reason of the color contrast between the light, preferably white, translucent layer, and the dark, preferably black, opaque outer layer.

The clarity of the internally illuminated indicia is increased by providing a translucent layer having improved transilluminating or light transmitting characteristics. I have found that a layer of appreciable thickness, that is, preferably of a thickness of .003 to .008 inch, and formed of a clear plastic material having a dispersion of relatively large particles of white pigment suspended therein as an emulsion best performs this function. The further apart the white pigment particles are disposed within the clear plastic, the better are the light transmitting characteristics of the resulting translucent layer, as the transilluminating rays then cross the layer by reflection

from one particle to the next, as illustrated by the arrows in Fig. 4 shown reflected from particle to particle within the clear material of the layer 21. The spacing apart of the particles of white pigment does not excessively affect the ability of the translucent layer to reflect ambient light at the exposed portions of its outer surface, as ambient light generally impinges against these exposed portions from all directions.

A method of manufacturing a translucent layer of the kind described above consists of mixing a sufficient quantity of small, preferably polished, white pigment particles, into a clear resin, such as, for example, one of the class of acrylic resins. The mixing may be done in a Banbury mixer, commonly known in the art, which blends in the particles of pigment under heat. If desired, phosphorescent pigments may also be introduced into the mixture.

The above mixture is then rolled or calendered into sheets of the desired thickness.

It has been found that attempts to produce a similar wide dispersion of the pigment particles in a paint, results in a paint or lacquer which is so thin as to provide a coat of only .00025 or .0005 inch and in such thin coats or layers the particles are not widely dispersed across the depth of the layers or coats.

While Fig. 4 illustrates the widely dispersed particles of pigment in the layer 21 of the panel 17, it is to be understood that the translucent layer 13 in panel 10 of Figs. 1 and 2 is similarly formed.

Although I have described specific embodiments of the present invention, it is to be understood that my invention is not limited to these precise embodiments and that various changes and modifications, obvious to one skilled in the art, may be made therein without departing from the spirit or scope of the invention as defined in the appended claims.

What is claimed as new and desired to be secured by Letters Patent is:

1. A panel comprising front and back layers of translucent material enclosing a light-transmitting medium therebetween, and outer layers of opaque material superimposed on said layers of translucent material, the outer layer of opaque material covering said front layer of translucent material being formed with at least one opening therethrough covered at its inner end by said front layer of translucent material, said panel having light source means therein for admitting light to the light-transmitting medium to transilluminate the translucent layer at the inner end of the opening formed in the front opaque layer, said back translucent layer and the opaque layer superimposed thereon being substantially flat and said front translucent layer and the opaque layer superimposed thereon being curved to incline the portions thereof remote from said light admitting means progressively toward the latter.

2. A panel according to claim 1, wherein said front translucent layer and the opaque layer superimposed thereon are outwardly convex and curved symmetrically with respect to said light source means, and said light source means is disposed at the portion of the panel having the greatest distance between the front and back translucent layers and at a distance from said front translucent layer substantially smaller than the radius of curvature of said front translucent layer.

3. A panel according to claim 1, wherein said light-transmitting medium is formed by a core of solid transparent material.

4. A panel according to claim 1, wherein said outer layers of opaque material are provided by a hollow box structure, said translucent layers being carried by the internal wall surfaces of said box structure, and wherein said light transmitting medium consists of air contained in the hollow interior of said box structure.

5. A panel comprising a hollow box structure including spaced front and back walls, a layer of translucent material covering the interior surfaces of said box structure, said front wall having at least one opening therethrough closed at its inner end by the underlying portion of said translucent layer, and means for admitting light to the hollow interior of said box structure to transilluminate the translucent layer at the opening in said front wall.

6. A panel as set forth in claim 5, wherein said front wall is curved to progressively incline the portions of said translucent layer carried thereby and remote from said light admitting means toward the latter, said back wall being substantially flat.

7. A panel as set forth in claim 5, wherein said front wall is outwardly convex, and said light admitting means is disposed at the location in which said front and rear walls are spaced apart the maximum so that the portions of said translucent layer carried by said front wall and remote from said light admitting means are disposed to transmit light outwardly to the front surface of the panel with substantially the same intensity as the portions of the translucent layer adjacent to said light admitting means.

8. A panel comprising front and back layers formed of a clear light transmitting material having widely dispersed pigment particles suspended therein, said front and back layers enclosing a light-transmitting medium therebetween, and outer layers of opaque material superimposed on said front and back layers, the outer layer of opaque material covering said front layer having an opening therethrough covered at its inner end by said front layer, said panel having means for admitting light to the light-transmitting medium between said front and back layers to transilluminate the front layer at said opening in the covering opaque layer.

9. A panel as set forth in claim 8, wherein said light-transmitting medium is formed by a core of solid transparent material laminated between said front and rear layers.

10. A panel as set forth in claim 8, wherein said front layer and the opaque layer superimposed thereon are outwardly convex and said light admitting means is disposed at the thickest portion of the panel with the con-

vexity being symmetrical thereabout so that the parts of said front layer remote from said light admitting means are inclined toward the latter to equalize the transillumination through said front layer, said back layer being flat and said light admitting means being disposed at a distance from said front layer substantially less than the radius of curvature of the latter.

11. A panel as set forth in claim 8, wherein said outer layers of opaque material are provided by a hollow box structure, said front and back layers being carried by the internal wall surfaces of said box structure, and wherein said light transmitting medium consists of air contained in the hollow interior of said box structure.

12. A panel as set forth in claim 11, wherein, the wall of said hollow box structure carrying said front layer is curved to substantially equalize the transillumination of said front layer.
